Application February 28, 1952, Serial No. 18,694

Term of patent 14 years

(Cl. D13—1)

To all whom it may concern:

Be it known that we, Benjamin Cooper, a citizen of United States, residing at New York, in the county of New York and State of New York, and Stanley A. Kroll, a citizen of United States, residing at Brooklyn, in the county of Kings and State of New York, have invented a new, original, and ornamental Design for a Toll Station or Similar Article, of which the following is a specification, reference being had to the accompanying drawing, forming part thereof.

In the drawing:

Fig. 1 is a front perspective view of a toll station showing our new design:

Fig. 2 is a rear elevation of the toll station:

Fig. 3 is a partial end view of the toll station;

Fig. 4 is an outline of the toll station taken along line 4—4 of Fig. 2.

We claim:

The ornamental design for a toll station or similar article, substantially as shown.

BENJAMIN COOPER.

STANLEY A. KROLL.
